[57] CLAIM

The ornamental design for an icon for user profile or the like, as shown and described.

DESCRIPTION

FIG. 1 is a face view of an icon for user profile or the like showing our new design in display position; FIG. 2 is a face view of the icon alone;

FIG. 3 is a face view of an icon for user profile or the like showing a modified form of our new design; FIG. 4 is a face view of a smaller embodiment of the icon in FIG. 2;

FIG. 5 is a face view of a smaller embodiment of the icon in FIG. 3; and,

FIG. 6 is a face view of the icon in FIG. 2 on an enlarged scale.

The broken line showing of a partial half tone display screen in FIG. 1 is for illustrative purposes only and forms no part of the claimed design.
